Primary Examiner — Robert M Spear*Assistant Examiner* — Marissa J Cash*(74) Attorney, Agent, or Firm* — Thompson Coburn LLP(57) CLAIM

We claim the ornamental design for a the cap for drinking and misting for beverage bottles, as shown and described.

DESCRIPTION

FIG. 1 is a perspective view taken from the right front corner of the cap for drinking and misting for beverage bottles showing our new design;

FIG. 2 is a perspective view taken from the left bottom rear corner of the cap for drinking and misting for beverage bottles;

FIG. 3 is a right side view thereof;

FIG. 4 is a left side view thereof;

FIG. 5 is a front view thereof;

FIG. 6 is a rear view thereof;

FIG. 7 is a top plan view thereof; and,

FIG. 8 is a bottom view thereof.

The broken lines in the drawings depict environmental subject matter only and form no part of the claimed design.
